UNITED STATES PATENT OFFICE.

HUGH GELLROY BUCHAN, OF NEWARK, NEW JERSEY.

BINDER AND SECURING-CLIP JOINT THEREFOR.

984,120.

Specification of Letters Patent. Patented Feb. 14, 1911.

Application filed August 19, 1909. Serial No. 513,689.

To all whom it may concern:

Be it known that I, HUGH GELLROY BUCHAN, of the city of Newark, in the county of Essex and State of New Jersey, have invented certain new and useful Improvements in Binders and Securing-Clip Joints Therefor and for other Purposes, of which the following is a specification.

The objects of my invention, are first, to provide a cheap, simple and strong securing-clip for use in mechanically, and without the aid of adhesives, securing strips or sheets of leather or other flexible fabrics to the edges of metallic strips or straight edges, which strips or straight edges are usually but not necessarily of segmental form in cross-section; and second, to provide bindings of all sorts, having a metallic or partially metallic back-piece, whether such binders are of the form known as loose or removable leaf-binders, or are permanent binding with such mechanical securing or locking clip, by the use of which the side pieces or binding boards of the binder may be easily and quickly secured to the back-piece, in such manner as to be absolutely safe against any but intentional separation therefrom.

My said invention consists broadly in the discovery of the fact, and practical application thereof, that when a flexible fabric is doubled upon itself, and the fold thereof pressed by the edge of a sheet or straight edge of metal, which is preferably but not necessarily of segmental form in cross-section, through the longitudinal slit in the peripheral wall of a substantially cylindrical tube and into the interior of such tube, (which is preferably of brass or other resilient spring metal), and a free end of the fabric is then drawn tightly around the periphery of the tube, that the tighter the fabric is so drawn, the more securely will this drawing, by the straining around the tube exerted upon one side of the slit, so rock the tube upon the sheet as to lock the fabric to the tube by the pressure thus brought upon the fabric by the opposite side of the slit; and it is self evident from an examination of the drawing, that when properly made and proportioned, and put together, this new and improved joint of my invention, thus made between the fabric and the straight edge, cannot be unintentionally separated save by fracture.

Said invention is fully shown and described in the following specification, of

which the accompanying drawing forms a part, wherein similar letters or numerals of reference designate like or equivalent parts, wherever found throughout the several views, and in which—

Figure 1 is an end view in central cross section of the rear or back-piece side of a binder of loose leaf form, showing my said invention applied thereto; Fig. 2 is a side view in detail, partially in central vertical section, of the sleeve-nut and its pivot connection with the lower segment of the back-piece, forming a portion of the locking mechanism of my improved form of binder; Fig. 3 is a like end view of that portion of Fig. 1, showing my said invention of the securing-clip and its self-locking action; and Fig. 4 is a view in detail of the slotted substantially cylindrical clip-tube, which is more fully shown in Figs. 1 and 3, and which in combination with the co-acting parts shown in said Figs. 1 and 3, forms the substance and essence of my invention.

Referring to the drawings: The reference letter A designates the binding board and B the body of loose leaves bound.

C designates the upper and C' the lower of two metallic substantially segmental shaped back-pieces, which together form the back of the binder, which are hinged together at their rear and abutting edges by the hollow coiled portions 11, formed integral therewith, which in combination with the hinge-bolt 13', joining them together, form a hinge joint as shown; so that upon screwing the lock-screw-bolt 16 fully out of the co-acting sleeve-nut 18, (which is pivotally secured to the bottom segment C' of the back-piece by a joint 19' which permits such sleeve-nut to rock to the front and rear), the upper segment C of the back-piece together with the top cover board, may be thrown back into the open position shown in Fig. 3, when the loose leaves B may be wholly or in part removed from the binder and new ones inserted; and upon closing the hinge segments together again, and screwing the lock-screw-bolt 16 fully home into the sleeve-nut 18, the new bundle of loose leaves will be firmly bound therein and the binder be again ready for use.

The two cover-boards A are usually secured together by an outer more or less flexible back-covering piece 23, formed integral with or secured to such boards in any desired manner, which back-covering piece 23

extends from one of such boards A around over the outside of the segments C and C' to the other board, and each of such cover-boards A is firmly secured to the segment 5 adjacent thereto at the forward outer edge thereof by a flexible backing or securing strip 20', usually of leather or other suitable stout flexible fabric, which is firmly glued or otherwise secured to the cover-board A 10 on that side, as shown at 34, by means of a securing-clip 21, which clip, and the non-adhesively secured joint of which such clip forms a part, is the main portion and essence of my invention, set forth, described 15 and claimed herein, whether used in book binding or for other purposes.

As shown in detail in Fig. 4 and in cross-section and under strain in Fig. 3, my improved securing-clip 21 consists of a tube of 20 resilient metal, usually spring-brass, which is substantially cylindrical or circular in cross-section, and is provided with a narrow longitudinal slit 35, preferably extending from end to end thereof, of such width 25 that considerable force must necessarily be used to force the slotted tube down over the flexible backing-strip 20', when the same is doubled or folded over the straight edge of one of the segmental pieces C or C', and 30 into the position shown in Figs. 1 and 3. And it is self-evident from the drawing, that when in such position, strain upon the flexible backing-strip 20', however great, cannot draw the same out of the clip-tube s such 35 strain is always exerted around and *pon* the peripheral surface thereof, so as to cause a rocking movement of such tube upon its axis by the strain and pressure exerted upon the inner edge *a* of the slit 35, which would 40 cause an inward movement of the outer edge of the slit, as shown greatly exaggerated in Fig. 3, so as to bring about a biting and binding pressure upon the fabric 20' at the point *b*, so as to bind the same 45 firmly upon the segment C or C', which biting and binding action will always increase with the strain upon the fabric 20' in such ratio as to prevent any drawing away of the same from the tube and segment. 50

To form the cheap and efficient pivot joint 19' of my improved form, which I prefer to use in securing the sleeve-nut 18 to the bottom segment C', as shown in Figs. 1 55 and 2, the two lugs 32 are first swaged outward from the segment, so as to permit the insertion of the sleeve-nut 18; the side pivot lugs 33 of which sleeve-nut are formed integral therewith at the bottom on opposite 60 sides, extending outward at a right angle to the axis of the nut. After such insertion, the lugs 32 of the segment are swaged back into the securing position shown, against the rear and pivot end of the sleeve-nut, so 65 as to hold the lugs 33 firmly into the reversed

pivot depressions 34, formed in the segment C', by the swaging operation, all as clearly shown in detail in Fig. 2.

It will thus be seen that in my improved securing clip 21, and the joint between a straight edge and a flexible fabric of which the same forms a part, I have evolved and invented a perfect device for securing a fabric to a metal sheet or straight-edge, without the aid of rivets or adhesives; and 70 while I have shown my said invention as specifically applied herein to a segmental back-binder for loose leaves, etc., I do not intend to limit myself to such use, as such improved clip-joint and the principle applied herein, thereby may be applied in all cases where it is desired to bind a fabric to metal—and I do not intend to limit myself to the exact form of binder shown, nor even to the use of such invention in book 75 binders, as the same may be used in all cases where it is desired to secure a flexible fabric to a metallic or other straight-edge, whether of flat, curved or other form in cross-section, in any device, and for any purpose, without 80 departing from the scope of my invention. 85

I claim:—

1. A straight-edge, a flexible fabric folded over the straight-edge, and a securing-clip in the form of a slotted tube superposed 95 upon the folded fabric and straight-edge, the sheet of fabric being drawn around and over the periphery of the securing clip or slotted tube.

2. A straight-edge, a flexible fabric folded over the straight-edge, and a securing-clip in the form of a slotted tube of resilient 100 material superposed upon the folded fabric and straight-edge, the sheet of fabric being drawn around and over the periphery of the 105 securing clip or slotted tube.

3. A straight-edge, a flexible fabric folded over the straight-edge, and a securing-clip in the form of a slotted tube of substantially 110 cylindrical form in cross-section superposed upon the folded fabric and straight-edge, the sheet of fabric being drawn around and over the periphery of the securing clip or slotted tube.

4. A metallic straight-edge, a flexible fabric folded over the straight-edge, and a securing-clip in the form of a slotted tube superposed upon the folded fabric and straight-edge, the sheet of fabric being drawn around and over the periphery of the 115 securing clip or slotted tube.

5. A metallic straight-edge, a flexible fabric folded over the straight-edge, and a securing-clip of resilient spring metal in the form of a slotted-tube of substantially 120 cylindrical form in cross-section superposed upon the folded fabric and straight-edge, the sheet of fabric being drawn around and over the periphery of the securing clip or 125 slotted tube.

6. In a binder, two segmental shaped back-pieces secured together by cylindrical alternating hinge-joints formed integral with each of such segments, cover-boards, flexible backing-pieces secured to the cover-boards, a clip in the form of a longitudinally slitted tube of substantially cylindrical form in cross-section inclosing a fold of each of the flexible backing-pieces and the edge 10 of the segments of the back-piece, the securing edges of the flexible backing-pieces extending outward from the securing-clip and being secured to the cover-boards, and an outer flexible back-cover securing the 15 cover-boards together.
7. In a binder, two segmental shaped back-pieces secured together by cylindrical alternating hinge-joints formed integral with each of such segments, flexible backing- 20 pieces, and a clip in the form of a longitudinally slitted tube inclosing a fold of the flexible backing-piece and the edge of the segment, and securing the same upon the binding edge of each of the segments of the 25 back-piece.
8. In a binder, two segmental shaped back-pieces secured together by a hinge-joint, cover-boards, flexible backing-pieces, and a clip in the form of a longitudinally 30 slitted tube inclosing a fold of the flexible backing-piece and the edge of the segment and securing the same upon the binding edge of each of the segments of the back-piece, the edges of the flexible backing- 35 pieces extending outward from the securing-clip and being secured at the forward edges to the cover-board.
9. In a binder, a back-piece of substantially segmental shape in cross-section, 40 cover-boards, a flexible fabric backing-piece secured to each of the cover-boards, and a securing clip in the form of a longitudinally slitted tube around and over which the flexible fabric backing-piece passes from 45 the segment edge to the cover-board superposed upon a fold of the fabric over the edge of the segment.
10. In a binder, a back-piece of substantially segmental shape in cross-section formed of two segmental shaped pieces longitudinally hinged together, cover-boards, a flexible fabric backing-piece secured to each of the cover-boards, and a securing clip for each of the two segmental shaped pieces 55 in the form of a longitudinally slitted tube around and over which the flexible fabric backing-piece passes from the segment edge to the cover-board superposed upon a fold of the fabric over the edge of the segment.
- 60 11. A joint for book binders, etc., comprising a metallic back-piece of segmental form in cross-section, a flexible fabric backing-piece or strip folded over the edge of
- the metallic back-piece, and a metallic securing-clip in the form of a longitudinally slitted tube superposed upon the fold and back-piece edge, the sheet of fabric being drawn around and over the periphery of the securing clip or slitted tube. 65
12. A means for joining fabrics to straight edges of sheet metal, etc., comprising a fold in the fabric superposed upon the straight edge, and a longitudinally slitted tube superposed upon the fold; the sheet of fabric being drawn around and over the periphery of the securing-clip or slitted tube 70 in such manner that the fabric when drawn upon and put under strain will rock the slitted tube upon the straight edge, so as to bind the fabric firmly against the same. 75
13. A means for joining fabrics to straight edges of sheet metal, etc., comprising a fold in the fabric superposed upon the straight edge, and a longitudinally slitted tube of substantially cylindrical form in cross-section, superposed upon the fold; the sheet of fabric being drawn around and over the periphery of the securing-clip or slitted tube in such manner that the fabric when drawn upon and put under strain will rock the slitted tube upon the straight edge, so as to bind the fabric firmly against the same. 80
14. In a binder, a back-piece of substantially segmental shape in cross-section, 85 cover-boards, a flexible fabric backing-piece secured to each of the cover-boards, and a securing clip in the form of a longitudinally slitted tube around and over which the flexible fabric backing-piece 90 passes from the segment edge to the cover-board, superposed upon a fold of the fabric over the edge of the segment, and a flexible back covering-piece extending over and around the segmental back-piece from 95 one cover-board to the other.
15. In a binder, a back-piece of substantially segmental shape in cross-section formed of two segmental shaped pieces longitudinally hinged together, cover-boards, a 100 flexible fabric backing-piece secured to each of the cover-boards, and a securing clip in the form of a longitudinally slitted tube around and over which the flexible fabric 105 backing-piece passes from the segment edge to the cover-board superposed upon a fold of the fabric over the edge of the segment, and a flexible back covering-piece extending over and around the segmental back-piece from one cover-board to the other. 110
16. In a binder, a back-piece of substantially segmental shape in cross-section formed of two segmental shaped pieces longitudinally hinged together, cover-boards, a flexible fabric backing-piece secured to each of the cover-boards, and a securing clip in the form of a longitudinally slitted tube around and over which the flexible fabric 115 backing-piece passes from the segment edge to the cover-board superposed upon a fold of the fabric over the edge of the segment, and a flexible back covering-piece extending over and around the segmental back-piece from one cover-board to the other. 120

Signed at the city of New York, August 18, 1909.

HUGH GELLROY BUCHAN.
